HENRY H. HAYDEN, OF NEW YORK, N. Y., ASSIGNOR TO HOLMES, BOOTH, AND HAYDENS, OF WATERBURY, CONNECTICUT.

Design No. 3,300, dated December 29, 1868.

DESIGN FOR THE HANDLE OF A FORK OR SPOON.

The Schedule referred to in these Letters Patent and making part of the same.

To all whom it may concern:

Be it known that I, HENRY H. HAYDEN, of the city and State of New York, have invented or produced a new and original Design for the Handles of Forks, Spoons, &c.; and I do hereby declare the following to be a correct description of the same, reference being had to the annexed photograph, representing the design of the said handle, in—

Figure 1, as upon a spoon, and in

Figure 2, as upon a fork.

My invention relates to the ornamental shape of the outline or configuration of the handle, near the end thereof.

Commencing at the points *a a*, the sides of the handle diverge, in nearly a straight line, to the corners *b*, and the end of the said handle is arched between

the said points *b b*, and provided with a central arched ornament, *c*.

The raised ornamentation on the surface of said handle forms no part of this present design.

What I claim, and desire to secure by Letters Patent, is—

The design of the ornamental shape and configuration of the outline *a b c b a* of the handle, substantially as represented.

In witness whereof, I have hereunto set my signature, this 17th day of April, A. D. 1868.

H. H. HAYDEN.

Witnesses:

CHAS. H. SMITH,
GEO. DENNETT WALKER.
